(22) Filed: **Sep. 25, 2009**

The ornamental design for the valving element for butterfly valve, as shown and described.

(30) **Foreign Application Priority Data**

DESCRIPTION

Mar. 31, 2009 (JP) 2009-007253

FIG. 1 a front perspective view of a valving element for butterfly valve showing my new design;

(51) **LOC (9) Cl.** **23-01**

FIG. 2 is a rear perspective view thereof;

(52) **U.S. Cl.** **D23/233**

FIG. 3 is a front view thereof;

(58) **Field of Classification Search** D23/233-237,

FIG. 4 is a rear view thereof;

D23/244-249; 251/121, 205-209, 212-215,

FIG. 5 is a right side view thereof;

251/283, 286, 288, 292, 293, 304, 305, 307,

FIG. 6 is a left side view thereof;

251/309-315.01, 317, 317.01; 137/625.21,

FIG. 7 is a bottom view thereof;

137/625.23, 625.31

FIG. 8 is a cross-sectional view taken along line 8—8 of FIG. 3; and,

See application file for complete search history.

FIG. 9 is a cross-sectional view taken along line 9—9 of FIG. 3.

(56) **References Cited**

The dashed lines in the drawings represent unclaimed portions of the valving element and form no part of the claimed design. The dashed-dot lines in the drawings are boundary lines that define the claimed and unclaimed areas of the valving element, and form no part of the claimed design.
